TELEPHONE RECEIVER

Filed Dec. 10, 1925

UNITED STATES PATENT OFFICE.

WILLIAM E. LA PEARLE AND WILLIAM H. LA PEARLE, OF SALT LAKE CITY, UTAH.

TELEPHONE RECEIVER.

Application filed December 10, 1925. Serial No. 74,634.

This invention relates to sound reproducing devices of the telephone receiver type.

Primarily, the device is intended for use as part of a radio loud speaker, although it may well be used for other sound reproducing purposes.

By means of the invention, it is sought not only to provide for greater volume and increased sensitiveness in a device of this character, but also to effect a saving in cost and time of production and repair.

More specifically, it is intended to provide an improved mounting for the armature associated with the usual electro-magnet of the device, which will result in improved reproduction. The provision of facilities for ready adjustment of parts for tuning and other purposes are also objects of the invention.

With regard to repairs and replacements, particularly those involving the armature, special provisions are made so as to render these extremely simple and inexpensive. Heretofore, the armature has been so mounted that, in order to remove it for repair or other purposes, it has been necessary to first remove the electro-magnet and, in some cases, to entirely disassemble the electro-magnet. Some manufacturers, rather than take the time to do this, discard the entire electro-magnet, together with the armature, and replace these with new parts. The present invention provides a receiver in which the armature may be removed and replaced readily without disturbing the electro-magnet. Provision is also made to assure accurate reassembly of the parts with reference to each other.

Other objects will be apparent upon inspection of the following description and accompanying drawing in which—

Fig. 1, represents a side view of the device with most of the parts shown in section in order to disclose the interior construction;

Fig. 2, an end view of the device of Fig. 1, portions of the armature handling and positioning means being broken away in order to more clearly show its construction;

Fig. 3, a perspective view of the armature unit as it appears when removed, this being the preferred form of the unit and the same as that shown in Figs. 1 and 2;

Fig. 4, an end view from the left of the

armature unit of Fig. 3 showing the means for adjusting the armature balancing spring; 65

Fig. 5, a side view of a modified form of the armature unit;

Fig. 6, a similar view of another modified form of the armature unit;

Fig. 7, a sectional view taken on line 7—7 of Fig. 6;

Fig. 8, an outer end view of a modified form of the armature handling and positioning member;

Fig. 9, an end view of a modified form of the electro-magnet spool;

Fig. 10, a plan view of the same;

Fig. 11, a longitudinal section of another modified form of the armature unit; and

Fig. 12, an elevation looking towards the inner face of a further modified form of the armature unit.

In the drawing, disclosure of any form of base to which the device may be attached or casing in which it may be mounted is omitted for sake of clearness. Any suitable base or casing may be used.

The assembled device which constitutes the invention, is shown in Figs. 1 and 2. The permanent magnet 1 disclosed therein is of the usual U-shaped type, but any other type suitable for the purpose may be used. Supported on the upper leg 2 of permanent magnet 1 is the lower section 3 of the casing in which is mounted a diaphragm 4. Lower section 3 of the diaphragm casing is secured rigidly in place on the leg of the permanent magnet by means of suitable screws 5, 6 which extend through registering openings in the parts. Diaphragm 4 is clamped in position around its periphery by means of gaskets 7 and 8 located in the lower section 3 and the upper section 9 of the diaphragm casing. The two sections of the diaphragm casing are clamped together by means of a series of screws 10 which pass through suitable openings in the upper casing section 9 and are threaded into the lower section 3. Upper casing section 9 is provided centrally with a tubular, exteriorly-threaded extension 11 for attachment of the device to the base of a horn or other suitable sound-amplifying means. The form of extension 11 may be varied to conform to the construction of the sound amplifier to which it is to be attached. Permanent magnet 1 is provided at its

poles with U-shaped pole pieces 12 and 13. Pole piece 12 is secured rigidly in place on the inner face of leg 2 of the permanent magnet by means of screw 6 which is made sufficiently long to engage a suitable threaded opening in the base of pole piece 12. Pole piece 13 is connected rigidly to the lower leg 14 of permanent magnet 1 by means of a screw 15 extending through a suitable perforation in the leg of the magnet and threaded into the base of the pole piece.

Mounted transversely of permanent magnet 1 in its pole pieces 12 and 13 is an electro-magnet 16. The electro-magnet consists of the usual winding 17 and a flanged spool 18. Ordinarily the flattened tube portion 19 of spool 18 and the end flanges 20, 21 are both formed of metal, in which case the end flanges are separate pieces which are soldered into place on the ends of the tube portion. In the all-metal spool tube portion 19 is slotted at 22 and end flanges 20, 21 are slotted at 23, 24 respectively, so as to prevent eddy currents from affecting the magnetization of the armature of the device.

Sometimes it is desirable to use fiber end flanges on the electro-magnet spool 18, instead of the metal end pieces. In this case, as shown in Figs. 9 and 10, the tubular portion 19 of the spool, which is of metal, is slotted at 22, as in the all-metal spool of Figs. 1 and 2, but it is unnecessary to slot the fiber end pieces. The end pieces, 25, 27 being of fiber, cannot be soldered to the tubular portion 19, so in order to hold them in place before the winding 17 is put on tubular portion 19 is provided at its ends with extensions or ears 28 which are bent over against the outer faces of the flange pieces after they have been slipped on the tube 19. When the winding 17 is put in place, a very rigid and compact magnet structure is obtained which in use is free from eddy currents.

The armature 29 and its mounting and the means for positioning it in the device will now be described. The armature in its preferred form, as heretofore stated, is shown in Figs. 1-4 inclusive. As shown most clearly in Fig. 1, armature 29, when in operative position, extends horizontally through the tubular portion 19 of the electro-magnet 16 and projects beyond each end thereof. The armature is in the form of a thin, flat metal plate and at its inner end is provided with a perforated extension 30. A link 31, having a head 32 engaging the perforated extension 30 of armature 29, connects this end of armature 29 to diaphragm 4. In order to accommodate link 31, leg 2 of permanent magnet 1 is provided with an opening 33 therethrough and lower section 3 of the diaphragm casing has a registering opening 34 through which link 31 extends. The upper end of link 31, which is enlarged

and threaded, extends through a central opening provided in diaphragm 4. Mounted on the projecting threaded end of link 31 above diaphragm 4 is a threaded washer 35 and a nut 36 by means of which the tension 70 under which the diaphragm is placed may be varied to tune the instrument. Washer 35 and nut 36 being threaded on link 31, serve to lock each other in place and prevent accidental displacement of the tuned parts. 75

Detachably secured on the outer side of pole piece 12 by means of a screw 37 engaging a suitable threaded opening in the pole piece is a bracket member 38. This member is made of non-magnetic material 80 so as to prevent magnetization of armature 29, to which it is connected in a manner which will now be explained.

A U-shaped member 39, which is formed of fine spring wire, has its legs fixed, as by means of soldering, in the bracket member 38, as shown at 40, 41 (Figs. 1 and 5). The legs of member 39 extend out from bracket 38 above and parallel to armature 29 and, near its base portion member 39 is bent 90 at right angles and has the lower portions of its legs extending through suitable perforations located centrally in the armature 29. The legs of member 39 are soldered to the armature in this position, so that, as clearly shown in Fig. 1, the base and lower portions of the legs of member 39 project below the armature 29 a distance equal to that of the upper portions of the legs above the armature. In this manner, member 39 100 is made to serve a two-fold purpose. It functions as a central, transverse, pivotal support for armature 29 within the spool of the electro-magnet 16 and also as means 105 connecting the armature to bracket member 38, whereby the latter may be used, not only to remove and replace armature 29, but also to properly position it within the electro-magnet as will now be explained.

In order that armature 29 may function 110 properly in the operation of the receiver, it is desired that it be located centrally between the top and bottom walls of tubular portion 19 of the electro-magnet spool and the pole pieces 12, 13. This is simply and 115 accurately accomplished by the portions of member 39 above and below armature 29, which fit snugly into tubular portion 19 of the electro-magnet spool and serve to guide the armature 29 into proper position when the parts are being assembled. For the device to operate efficiently, it is also desired that armature 29 have its support or mounting, formed by member 39, located centrally 120 of the armature and centrally between the ends of the electro-magnet 16, as shown in Fig. 1. This is accomplished by properly proportioning the parts 38 and 39, so that when member 38 is secured in place by screw 37 the pivotal support of armature 29 will 125 130

be located in the exact center of electro-magnet 16.

In order to transmit the vibrations set up in armature 29 by electro-magnet 16, when the receiver is in operation, it is necessary that the connections between the inner end of armature 29 and diaphragm 4 be tightened up so as to place the diaphragm under tension. Means are provided on bracket member 38, in the form of a spring 42, for engaging the opposite or outer end of armature 29 to balance it against the tension of diaphragm 4. The lower part of bracket 38, as will be seen in Fig. 1, is shaped so that when in position it will not contact with the lower pole piece 13. Bracket member 38 has a depending portion 48 on the inner face of which is formed a pair of lugs 44, 45. One end of spring 42 is fixed, as by means of soldering, in lug 44 and its free end is disposed in a slot 46 provided in lug 45. Intermediate its ends spring 42 is bent so as to provide a bearing portion 47 which engages with an extension 48 formed on the outer end of armature 29. It will thus be seen that with spring 42 bearing against the under side of the outer end of armature 29, the armature will be balanced against the tension of diaphragm 4 which tends to pull the inner end of the armature upward. However, as one end of spring 42 is free, the spring will yield so as to permit the proper pivotal or vibratory operation of armature 29 by electro-magnet 16.

Means are provided on bracket member 38 for adjusting spring 42 with reference to armature 29. The adjusting means consists of a bracket 49 removably secured on the lower side of lug 45 in which is located a set screw 50. The set screw bears on spring 42 intermediate its fixed end and bearing portion 47. It is thus possible to adjust set screw 50 so as to vary the tension of the spring on armature 29 as may be desired, thereby tuning the instrument.

From the above description of the construction and arrangement of the parts of the device, the facility with which the armature unit may be removed for repair or other purposes will readily be seen. This may be accomplished without in any-wise disturbing the electro-magnet 16 by first removing nut 36 and washer 35 from the upper end of link 31 after which the link may be slipped downward through the perforated extension 30 of armature 29 and removed through the opening 51 provided for this purpose in the lower leg 14 of permanent magnet 1. Screw 37 is then removed, whereupon the entire armature unit may be taken out. The unit may then be repaired, or it may be retuned by means of set screw 50, after which it is replaced in the device, being guided into proper posi-

tion within the electro-magnet spool 18 by means of U-shaped member 39 and accurately located centrally of the ends of the electro-magnet by means of the bracket member 38 when the latter is in abutting relation to the outer face of pole piece 12. Screw 37 and the parts connecting the inner end of armature 29 to diaphragm 4 are then replaced and adjusted. The device is then ready for operation, except possibly for adjustment of washer 35, nut 36 and set screw 50 for tuning.

It will be noted that in the preferred form of the armature unit (Figs. 1-4), depending portion 48 of bracket member 38 so partially conceals from view spring 42 and the means for adjusting it. Fig. 8 shows a modified form of bracket member 38 in which the depending portion 48 of member 38 is omitted and lugs 44, 45 connected to the body of the bracket member by means of portions 52, 53, respectively. This arrangement permits a clearer view of the spring 42 and its adjusting means when the receiver is assembled.

In the modified forms of the armature unit shown in Figs. 5, 6 and 7, the adjusting means for spring 42 are omitted for sake of clearness and this is also done in Fig. 1.

In Fig. 5, the U-shaped member 39 for supporting and positioning armature 29 is replaced by a pair of spaced, vertically disposed U-shaped members 54, the free ends of which are fixed in bracket member 38, similar to the attachment of the legs of member 39 to member 38, as shown in Fig. 8. Only the front one of the pair of U-shaped members 54 is shown, the rear member being directly behind the front one and connected to armature 29 in the same manner as is the front member. Members 54 have their base portions extending through and fixed in openings provided for this purpose centrally in armature 29, thus forming the transverse pivotal mounting for the armature. With this arrangement a more substantial mounting is provided for armature 29 and the several legs of members 54 serve to increase the facility with which the armature may be positioned within the electro-magnet 16.

In the modified armature unit construction of Fig. 6 the transverse, pivotal mounting for armature 29 is formed by a vertically disposed plate 55 having a reduced lower portion 56 which extends through and is soldered, or otherwise secured, in a transverse slot provided centrally in armature 29. The portion of plate 55 projecting above armature 29 is connected to bracket member 38 by means of wires 57, 58, the ends of which are fixed in plate 55 and bracket member 38. This modified form of the armature unit is quite similar to that shown in Fig. 3, but more rugged.

Fig. 11 is a modified form of the armature unit in which the position of the pivotal spring member 39 with reference to armature 29 is reversed, so that the upper portions of the legs of member 39 are below and the base of member 39 is above the armature. This provides a still more efficient pivotal support for the armature.

In the form of armature unit shown in Fig. 12, the means for balancing and tuning armature 29 comprise an externally-threaded tubular member or screw 59, which is mounted for adjustment in a suitable threaded opening in the lower side of rectangular frame portion 48 of bracket 88; a pin 60, mounted for free lengthwise movement in tuning screw 59 and provided at its upper end with a tip 61 of non-resonant material bearing on the adjacent end of armature 29; an upper washer 62 which is fixed to pin 60; and a coil spring 63 mounted on pin 60 with its upper end bearing against washer 62 and its lower end against lower washer 64 which is mounted freely for lengthwise movement on the pin.

With this arrangement, not only does the non-resonant tip 61 of the pin dampen vibration of armature 29 at this point and thus prevent chattering, but the form of the tuning mechanism is more efficient and less likely to get out of order. A knurled or other suitable manipulating head 65 is formed on the outer end of tuning screw 59 and a lock nut 66 serves to secure the tuning screw in adjusted position.

With any one of the above described constructions, an extremely sensitive and durable armature unit is provided. The device, as a whole, is of simple construction and can be easily assembled and disassembled. It also requires but little adjusting to tune it. The armature unit can be mounted on any instrument having pole pieces and an electro-magnet arranged similarly to those of the present device.

In certain of the appended claims in speaking of the upper and lower surfaces of armature 29 the term "faces" or "opposite faces" is used and the armature is referred to as a "plate armature". This is done in order to make it clear that the armature is of the flat or "butterfly" type and therefore has opposite or upper and lower relatively broad faces as distinguished from its two opposite pairs of relatively thin edges. Consequently these terms in the claims are to be interpreted accordingly.

What is claimed is:

1. In a telephone receiver, the combination of a diaphragm; a permanent magnet; an electro-magnet, including a spool and a winding thereon; a plate armature disposed within said spool and adapted to be operated by the electro-magnet about a fixed pivot; armature supporting means disposed be-

tween and engaging the opposite faces of the armature and the adjacent faces of said spool for pivotally mounting the armature therein; and a connection between the armature and the diaphragm.

2. In a telephone receiver, the combination of a diaphragm; a permanent magnet; an electro-magnet, including a spool and a winding thereon; a centrally-pivoted plate armature disposed within said spool and adapted to be operated by the electro-magnet about a fixed pivot; a pivotal mounting for said armature comprising means connected to and extending centrally from opposite faces of the armature into engagement with said spool; and a connection between the armature and the diaphragm.

3. In telephonic apparatus, the combination of an electro-magnet, including a spool and a winding thereon; a centrally-pivoted plate armature located within said spool and adapted to be operated by the electro-magnet; and a pivotal mounting for the armature engaging with the opposite faces of the armature and the adjacent faces of the spool and provided with an extension projecting outside of the electro-magnet, said armature and its mounting being formed as a unit for ready insertion into and removal from said spool by means of said extension without disassembling the electro-magnet.

4. A removable armature unit for use in a telephone-receiver electro-magnet, which includes a spool and a winding thereon, comprising a centrally-pivoted plate armature adapted to be located within said spool for operation by the electro-magnet; and a pivotal mounting projecting centrally from the opposite faces of said armature for engagement with the interior of the spool to position the armature therein.

5. A removable armature unit for use in a telephone-receiver electro-magnet comprising a centrally pivoted plate armature adapted to be located within and operated by the electro-magnet; a pivotal mounting provided centrally of the upper and lower faces of the armature; and combined handling-and-positioning means for the unit located exteriorly of the electro-magnet and connected to said armature mounting.

6. A removable armature unit for use in a telephone receiver, including a permanent magnet having opposed pole pieces and an electro-magnet mounted in the pole pieces, comprising a centrally-pivoted armature adapted to be located within and operated by said electro-magnet; a combined handling-and-positioning member for the unit detachably secured to one of said pole pieces; and a pivotal mounting provided centrally of the armature and connected to the combined handling-and-positioning member.

7. A removable armature unit for use in

· a telephone receiver, including a permanent magnet, an electro-magnet and a diaphragm, comprising a centrally-pivoted armature intended to be located within and operated by said electro-magnet, one end of said armature being adapted to be connected under tension to said diaphragm; a pivotal mounting provided centrally of the armature for engagement with the interior of the electro-magnet; a handling-and-positioning member for the armature unit detachably mounted on the permanent magnet and connected to said pivotal mounting; and means mounted on said member to balance the armature against the tension of the diaphragm.

8. In a sound reproducing device of the telephone receiver type, a U-shaped permanent magnet having an opening through one of the legs thereof; a casing mounted on said leg of the permanent magnet; a diaphragm in said casing; an electro-magnet mounted between the poles of the permanent magnet; a pivoted armature located in the electro-magnet for operation thereby; and means connecting the armature with the diaphragm, said means extending through said opening in the leg of the permanent magnet, the other leg of the permanent magnet being provided with an opening therethrough to permit removal of said connecting means.

9. In a telephone receiver, the combination of a diaphragm; a permanent magnet; an electromagnet; a centrally pivoted plate armature located within and adapted to be operated by the electromagnet; removable,

combined handling-and-positioning means for said armature extending outside of the electro-magnet, means connecting one end of the armature to the diaphragm; and means to damp vibration of the opposite end of the armature, said damping means being carried by said handling-and-positioning means.

10. In a telephone receiver, the combination of a diaphragm; a permanent magnet; an electromagnet; a centrally pivoted armature adapted to be operated by the electro-magnet; means connecting one end of the armature to the diaphragm; and spring means for balancing the armature against the tension of the diaphragm, said means including a portion of non-resonant material bearing against the armature.

11. In a telephone receiver, the combination of a diaphragm; a permanent magnet; an electromagnet; a centrally pivoted armature adapted to be operated by the electro-magnet; means connecting one end of the armature to the diaphragm; a reciprocable member having one of its extremities formed of non-resonant material and bearing against the opposite end of the armature; a mounting for said reciprocable member; and spring means for maintaining said extremity of the reciprocable member in contact with the armature to balance it against the tension of the diaphragm.

In testimony whereof we have signed our names to this specification.

WILLIAM E. LA PEARLE.

WILLIAM H. LA PEARLE.

Fig. 11 is a modified form of the armature unit in which the position of the pivotal spring member 39 with reference to armature 29 is reversed, so that the upper portions of the legs of member 39 are below and the base of member 39 is above the armature. This provides a still more efficient pivotal support for the armature.

In the form of armature unit shown in Fig. 12, the means for balancing and tuning armature 29 comprise an externally-threaded tubular member or screw 59, which is mounted for adjustment in a suitable threaded opening in the lower side of rectangular frame portion 43 of bracket 38; a pin 60, mounted for free lengthwise movement in tuning screw 59 and provided at its upper end with a tip 61 of non-resonant material bearing on the adjacent end of armature 29; an upper washer 62 which is fixed to pin 60; and a coil spring 63 mounted on pin 60 with its upper end bearing against washer 62 and its lower end against lower washer 64 which is mounted freely for lengthwise movement on the pin.

With this arrangement, not only does the non-resonant tip 61 of the pin dampen vibration of armature 29 at this point and thus prevent chattering, but the form of the tuning mechanism is more efficient and less likely to get out of order. A knurled or other suitable manipulating head 65 is formed on the outer end of tuning screw 59 and a lock nut 66 serves to secure the tuning screw in adjusted position.

With any one of the above described constructions, an extremely sensitive and durable armature unit is provided. The device, as a whole, is of simple construction and can be easily assembled and disassembled. It also requires but little adjusting to tune it. The armature unit can be mounted on any instrument having pole pieces and an electro-magnet arranged similarly to those of the present device.

In certain of the appended claims in speaking of the upper and lower surfaces of armature 29 the term "faces" or "opposite faces" is used and the armature is referred to as a "plate armature". This is done in order to make it clear that the armature is of the flat or "butterfly" type and therefore has opposite or upper and lower relatively broad faces as distinguished from its two opposite pairs of relatively thin edges. Consequently these terms in the claims are to be interpreted accordingly.

What is claimed is:—

1. In a telephone receiver, the combination of a diaphragm; a permanent magnet; an electro-magnet, including a spool and a winding thereon; a plate armature disposed within said spool and adapted to be operated by the electro-magnet about a fixed pivot; armature supporting means disposed be-

tween and engaging the opposite faces of the armature and the adjacent faces of said spool for pivotally mounting the armature therein; and a connection between the armature and the diaphragm. 70

2. In a telephone receiver, the combination of a diaphragm; a permanent magnet; an electro-magnet, including a spool and a winding thereon; a centrally-pivoted plate armature disposed within said spool and adapted to be operated by the electro-magnet about a fixed pivot; a pivotal mounting for said armature comprising means connected to and extending centrally from opposite faces of the armature into engagement with said spool; and a connection between the armature and the diaphragm. 75

3. In telephonic apparatus, the combination of an electro-magnet, including a spool and a winding thereon; a centrally-pivoted plate armature located within said spool and adapted to be operated by the electro-magnet; and a pivotal mounting for the armature engaging with the opposite faces of the armature and the adjacent faces of the spool and provided with an extension projecting outside of the electro-magnet, said armature and its mounting being formed as a unit for ready insertion into and removal from said spool by means of said extension without disassembling the electro-magnet. 80

4. A removable armature unit for use in a telephone-receiver electro-magnet, which includes a spool and a winding thereon, comprising a centrally-pivoted plate armature adapted to be located within said spool for operation by the electro-magnet; and a pivotal mounting projecting centrally from the opposite faces of said armature for engagement with the interior of the spool to position the armature therein. 90

5. A removable armature unit for use in a telephone-receiver electro-magnet comprising a centrally pivoted plate armature adapted to be located within and operated by the electro-magnet; a pivotal mounting provided centrally of the upper and lower faces of the armature; and combined handling-and-positioning means for the unit located exteriorly of the electro-magnet and connected to said armature mounting. 105

6. A removable armature unit for use in a telephone receiver, including a permanent magnet having opposed pole pieces and an electro-magnet mounted in the pole pieces, comprising a centrally-pivoted armature adapted to be located within and operated by said electro-magnet; a combined handling-and-positioning member for the unit detachably secured to one of said pole pieces; and a pivotal mounting provided centrally of the armature and connected to the combined handling-and-positioning member. 115

7. A removable armature unit for use in 120

- a telephone receiver, including a permanent magnet, an electro-magnet and a diaphragm, comprising a centrally-pivoted armature intended to be located within and operated by said electro-magnet, one end of said armature being adapted to be connected under tension to said diaphragm; a pivotal mounting provided centrally of the armature for engagement with the interior of the electro-magnet; a handling-and-positioning member for the armature unit detachably mounted on the permanent magnet and connected to said pivotal mounting; and means mounted on said member to balance the armature against the tension of the diaphragm.
8. In a sound reproducing device of the telephone receiver type, a U-shaped permanent magnet having an opening through one of the legs thereof; a casing mounted on said leg of the permanent magnet; a diaphragm in said casing; an electro-magnet mounted between the poles of the permanent magnet; a pivoted armature located in the electro-magnet for operation thereby; and means connecting the armature with the diaphragm, said means extending through said opening in the leg of the permanent magnet, the other leg of the permanent magnet being provided with an opening therethrough to permit removal of said connecting means.
9. In a telephone receiver, the combination of a diaphragm; a permanent magnet; an electromagnet; a centrally pivoted plate armature located within and adapted to be operated by the electromagnet; removable, combined handling-and-positioning means for said armature extending outside of the electro-magnet, means connecting one end of the armature to the diaphragm; and means to damp vibration of the opposite end of the armature, said damping means being carried by said handling-and-positioning means.
10. In a telephone receiver, the combination of a diaphragm; a permanent magnet; an electromagnet; a centrally pivoted armature adapted to be operated by the electro-magnet; means connecting one end of the armature to the diaphragm; and spring means for balancing the armature against the tension of the diaphragm, said means including a portion of non-resonant material bearing against the armature.
11. In a telephone receiver, the combination of a diaphragm; a permanent magnet; an electromagnet; a centrally pivoted armature adapted to be operated by the electro-magnet; means connecting one end of the armature to the diaphragm; a reciprocable member having one of its extremities formed of non-resonant material and bearing against the opposite end of the armature; a mounting for said reciprocable member; and spring means for maintaining said extremity of the reciprocable member in contact with the armature to balance it against the tension of the diaphragm.

In testimony whereof we have signed our names to this specification.
